US0D1021993S

(12) **United States Design Patent** (10) Patent No.: **US D1,021,993 S**
(45) Date of Patent: ** Apr. 9, 2024

(54) **CAMERA FOR TELEVISION RECEIVER**

(71) Applicant: **LG ELECTRONICS INC.**, Seoul (KR)

(72) Inventors: **Younghun Jang**, Seoul (KR); **Hyojin Won**, Seoul (KR); **Seokhyun Park**, Seoul (KR)

(73) Assignee: **LG ELECTRONICS INC.**, Seoul (KR)

(**) Term: **15 Years**

(21) Appl. No.: **35/516,008**

(22) Filed: **Dec. 27, 2022**

(80) **Hague Agreement Data**

Int. Filing Date: **Dec. 27, 2022**

Int. Reg. No.: **DM/226028**

Int. Reg. Date: **Dec. 27, 2022**

Int. Reg. Pub. Date: **Jan. 20, 2023**

(30) **Foreign Application Priority Data**

Jul. 14, 2022 (KR) 30-2022-0028394

(51) **LOC (14) Cl.** **16-01**

(52) **U.S. Cl.**

USPC **D16/202**

(57) **CLAIM**

The ornamental design for a camera for television receiver, as shown and described.

DESCRIPTION

1 . Camera for television receiver

1.1 : Front perspective

1.2 : Rear perspective

1.3 : Front

1.4 : Rear

1.5 : Left

1.6 : Right

1.7 : Top

1.8 : Bottom

1.9 : Front perspective in an alternate state of use

1.10 : Front perspective in an alternate state of use with environment

1.11 : Rear perspective in an alternate state of use with environment

The broken lines indicate portions of the article that form no part of the claimed design; the broken lines showing a portion of a television receiver in reproductions 1.10 and 1.11 illustrate environmental structure and form no part of the claimed design.

1 Claim, 11 Drawing Sheets
